UNITED STATES PATENT OFFICE

161,117

MERCHANDISE DISPLAY STAND

Norton W. Moody, Flushing, N. Y.

Application September 25, 1948, Serial No. 148,773

Term of patent 14 years

(Cl. D80—9)

To all whom it may concern:

Be it known that I, Norton W. Moody, a citizen of the United States of America, residing at Flushing, in the county of Queens and State of New York, have invented a new, original, and ornamental Design for a Merchandise Display Stand, of which the following is a specification, reference being had to the accompanying drawings, forming a part hereof.

In the drawings,

Fig. 1 is a perspective view of a merchandise display stand, showing my new design;

Fig. 2 is a front elevational view on a slightly reduced scale; and

Fig. 3 is an end elevational view on a slightly reduced scale.

I claim:

The ornamental design for a merchandise display stand, substantially as shown.

NORTON W. MOODY.
